(57) CLAIM

The ornamental design for a refuse container lid, as shown and described.

DESCRIPTION

FIG. 1 is a top frontal perspective view of a refuse container lid according to my new design;

FIG. 2 is a right side view of the embodiment shown in FIG. 1;

FIG. 3 is a left side view of the embodiment shown in FIG. 1;

FIG. 4 is a back view of the embodiment shown in FIG. 1;

FIG. 5 is a front view of the embodiment shown in FIG. 1;

FIG. 6 is a bottom view of the embodiment shown in FIG. 1;

FIG. 7 is a bottom view of the embodiment shown in FIG. 1 with the environmental structure removed for clarity; and,

FIG. 8 is a top view of the embodiment shown in FIG. 1. The broken lines in the drawings are for illustrative purposes only and form no part of the claimed design.
